Primary Examiner — David Muller*Assistant Examiner* — Nathan Johnston(74) *Attorney, Agent, or Firm* — David B. Gornish;
Eckert Seamans Cherin & Mellott LLC(57) **CLAIM**

The ornamental design for a cannula sensor carrier, as shown and described.

DESCRIPTION

FIG. 1 is a front isometric view of a cannula sensor carrier showing our new design;

FIG. 2 is a rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 4 Drawing Sheets(56)
